UNITED STATES PATENT OFFICE

2,418,957

KNITTED GLOVE AND MAKING SAME

Eric Simmat, Wyomissing Hills, Pa., assignor to
The Nolde and Horst Company, Reading, Pa.,
a corporation of Pennsylvania

Application September 12, 1945, Serial No. 615,726

3 Claims. (Cl. 66—174)

1

My invention relates to a new and improved seamless knitted glove, and to a novel method of making the same on a suitable knitting machine, and my object is to produce a high quality glove, continuously formed as an integral unit, and fashion-knitted to hand-conforming shape so as to neatly fit without distorting stretch and strain, and insure a more pleasing appearance, greater comfort, and longer wearing qualities.

More particularly my invention relates to a glove of improved construction, comprising a hand portion, fashion-knitted along one of its side edges to form an accommodating shape and location for the glove thumb and its junction with the palm, and fashion-knitted across its upper hand end to form stepped-level finger divisions for proper fit-disposition of the finger extensions therefrom. And it further relates to a novel method of knitting a glove having such fashioned hand portion and thumb and finger extensions by a continuous production in sequential order of its component parts to form a complete integral seamless glove unit.

The nature of my improved glove aforesaid, and the method of making the same, and its manifest improvements and advantages, will now be more fully described in connection with the accompanying drawings, and the novel features involved specifically defined in the appended claims.

In the drawings:

Fig. 1 indicates a front elevation of a completed glove made in accordance with my invention and embodying my improved fashioned construction.

Fig. 2 is a similar view of the integrally knitted blank for forming the completed glove shown in Fig. 1.

Figs. 3 to 10 inclusive indicate diagrammatically and in sequential order my method of integrally knitting the component sectional portions of the blank of Fig. 2, for forming my improved glove.

Figs. 11 and 12, indicate diagrammatically, respectively in plan and side views, the disposition of the needles in a known type of knitting machine adapted to produce my improved glove.

As shown in the drawings, my glove comprises the usual component sections, of a wrist portion 5, a hand portion 6, a thumb portion 7, and four finger portions 8, 9, 10 and 11. And these portions, in accordance with my invention, and as later herein more fully described, are knitted in a sequential order and fashion-shaped to provide a lateral extension 6a at one side edge of the hand portion 6 so as to accommodate the base of a thumb joint and suitably locate the thumb portion 7 laterally of said hand portion at the upper end of said extension 6a to receive a thumb without distortion of the knitted fabric. And the up-

2

per end of the hand portion 6 is further fashioned into finger divisions 8a, 9a, 10a and 11a, arranged in varied levels of stepped relation, so that the finger extensions therefor, 8, 9, 10 and 11 respectively, will have their junctions with the hand portion 6 at suitably fashioned variance to fit between the several fingers and extend to the base junctions of said fingers without stretch or distortion of the knitted fabric. As thus fashioned, it will be evident and readily understood, my improved glove will accommodate and fit a hand without stretch or strain, insuring greater comfort, a more pleasing appearance, and a longer wearing usefulness.

15 My improved glove, as above set forth, may be made on a well-known type of knitting machine more fully shown and described in U. S. Letters Patent No. 616,600 of December 27, 1898, and comprising inclined parallel rows of knitting needles 15 and 16, as indicated in Figs. 11 and 12, with provision for interknitting of end needles of any sectional division of said rows to form a corresponding width of tubular fabric, which may be widened or narrowed by adding or removing end needles from the knitting operation in usual manner, well-known, and readily understood without further description herein. By suitable control of the knitting operations of such known type of knitting machine I produce my improved glove in a new manner and method as will now be described.

Referring now particularly to Figs. 3 to 10, I first provide the wrist portion 5, which may, if desired, be separately fabricated and topped on the rows of needles 15 and 16, but which I prefer to knit on said needles as the initial step of my method, to form a tube of suitable length as shown in Fig. 3. To the upper course of loops of this tube 5 I continue knitting successive courses, and in accordance with my invention, fashion the tubular fabric they produce by adding needles in such successive courses at one side edge to produce the angular extension 6a, tapering outwardly from the wrist and to a laterally extended top course of loops 6b at substantially a mid-height part of the hand portion 6, as indicated in Fig. 4. I then continue knitting to the loops 6b to form the thumb 7, and hold the remaining loops of the top course of such partially knitted hand portion 6, retained on the needles but not knitting, as indicated in Fig. 5. After knitting to the loops 6b a tube of sufficient length for the thumb 7, I cast off this thumb fabric and withdraw from the knitting operation the needles that produced the same, and restore the remaining needles engaged with the loops of said partial hand portion to the knitting operation to complete a fabric length suitable for the hand portion 6. In accordance with my invention, the upper end of this hand portion 6 is fashioned as indicated in Fig. 6, by

removing from knitting, but holding on the needles, certain loops to produce the little finger extension 11, forming a stepped level 11a therefor, and continuing to knit a few courses on the remaining needles. Then the loops to produce the first finger 8 are withdrawn from knitting and held on the needles to produce the stepped level 8a, and knitting further courses on the remaining needles is continued, and loops to produce the ring finger 10 are then withdrawn from knitting and held on the needles to produce the stepped levels 10a. A few courses may if desired then be knitted on the remaining needles to form the stepped level 9a for finger extension 9. As thus far produced the knitted blank comprises the wrist portion 5, the fashioned hand portion 6 with the thumb extension 7 knitted thereto outside one side edge of said hand portion, and having a distinctive and ornamental inclined line of fashioning loops 20 indicating its fashioned construction. The upper end of the hand portion 6 is also fashioned as described into stepped levels 11a, 10a, 9a, and 8a, each of a width for a corresponding tubular finger extension, and the loops of each step held retained on their respective needles, each of such stepped levels desirably conforming to the point of junction at the base of its respective adjacent fingers with the palm of a hand.

The blank thus produced may be completed by the addition of finger tubes to the several divisions of stepped levels at the upper end of said hand portion 6, and the order of their production may be varied, but I prefer first to continue knitting a finger tube first to level 8a and complete the necessary length of tubular fabric and cast it off and withdraw its needles for the knitting operation. And then in similar manner to knit a finger tube to level 9a, then 10a, and finally to 11a, as indicated respectively in Figs. 7, 8, 9 and 10, and thus complete the glove blank indicated in Fig. 2, which clearly shows the varied levels of the finger junction with the hand portion, as desired. As heretofore and common practice in knitting gloves, certain loops of adjacent fingers will be interknitted at their point of junction with the hand portion 6 so as to form a closed crotch between the bases of said fingers. And the glove may be completed by utilizing the floating unknitted ends of the yarn at each finger top, to be engaged through the end loops of the latter to draw them together to close said finger tips, as indicated in the completed glove of Fig. 1.

From the foregoing description it is believed the nature of my improved glove and my novel method of making the same may be readily understood. And it will be readily apparent that such glove is actually knitted and fashioned to shape to fit a hand in a neat and undistorted manner, and the line of fashioning loops not only distinctively indicates its fashioned fabrication, but adds a pleasing ornamentation to the glove. And it will be understood that certain modifications and changes both in construction details and order of sequential production may be made without departing from the spirit of my invention as defined in the following claims.

What I claim is:

1. The method of making a seamless tubular glove, which consists in knitting to the wrist portion thereof a partial section of a tubular hand

portion having a fashioned side edge angularly widening from its wrist-end connection to a laterally-extending upper end, knitting a tubular thumb portion to said laterally extending upper end, knitting a continuing tubular section to said hand portion not connected to said thumb tube portion and fashioning the upper end of said tubular continuing section into finger-connecting divisions in a stepped relation at a varied transverse level, then adding in sequential order separate finger tube portions to said respective finger divisions, and completing the glove by a drawstring tied engagement of the upper loops of each finger and thumb tube to close together their top ends.

2. The method of making a fashioned hand-fitting integrally knitted seamless tubular glove, which comprises knitting a wrist-band portion, knitting to the top edge of said wrist-band portion a partial seamless tubular hand portion section having at one side thereof an integral gradually widening fashioned section extending upwardly from adjacent said wrist-band to a laterally projecting extension of the upper end of said hand portion section, knitting a seamless tubular thumb portion to said laterally projecting upper end extension, knitting to the remaining portion of said upper end a completing seamless tubular hand portion extension of uniform width, fashioning the upper end of said completing extension into hand-fitting separate finger-connecting sections, separately knitting seamless tubular finger portions to the respective fashioned finger-connecting sections, and closing 35 the top ends of said thumb and finger tubes by an independent non-knitting operation.

3. An integral fashion-knitted seamless tubular glove having hand-fitting seamless tubular thumb and finger extensions, comprising a seamless tubular hand portion having a straight side edge and a fashioned opposite side edge angularly widening from its lower end to a thumb-connecting upper end projecting laterally from said hand portion midway of its length, and a fashioned hand portion upper end having separate finger-connecting divisions at stepped hand-fitting levels, a seamless tubular thumb extension adjacent one side of said hand portion having its lower end connected to said mid-length lateral projection from the latter, and separate seamless tubular finger extensions from the upper end of said hand portion each having its lower end connected to its respective stepped division of the latter.
